DESIGN FOR A FINGER RING

Arthur Marcus, New York, N. Y.

Application November 9, 1945, Serial No. 123,632

Term of patent 7 years

(Cl. D45—10)

To all whom it may concern:

Be it known that I, Arthur Marcus, a citizen of the United States of America and residing in New York city, New York, have invented a new, original, and ornamental Design for Finger Rings, of which the following is a specification, reference being had to the accompanying drawing, forming part thereof.

Figure 1 is a top plan view of a finger ring showing my new design;

Figure 2 is a side elevational view of the same; Figure 3 is an elevational view of the side opposite that shown in Figure 2; and

Figure 4 is a bottom edge view of the ring, as shown in Figure 1.

I claim:

The ornamental design for a finger ring, as shown.

ARTHUR MARCUS.
